UNITED STATES PATENT OFFICE.

STEPHEN B. LEWIS AND FRANKLIN F. LEWIS, OF JANESVILLE, WISCONSIN,
ASSIGNORS TO THE LEWIS KNITTING COMPANY, OF SAME PLACE.

KNIT GARMENT.

SPECIFICATION forming part of Letters Patent No. 508,429, dated November 14, 1893.

Application filed January 7, 1893. Serial No. 457,592. (No model.)

To all whom it may concern:

Be it known that we, STEPHEN B. LEWIS and FRANKLIN F. LEWIS, citizens of the United States, residing at Janesville, in the county of Rock and State of Wisconsin, have invented 5 certain new and useful Improvements in Knit Garments, of which the following is a specification.

Our invention relates to knit garments, and 10 consists of a pair of drawers, union suit, pants, or similar garment to be worn about the legs and waist, in which the waist band is less elastic than the body portion, as hereinafter set forth and claimed.

15 In the drawings,—Figure 1 is a perspective view of a pair of drawers constructed in accordance with our invention; and Fig. 2, a sectional view on the line α — α .

In the manufacture of elastic shirts, drawers, skirts, suits, &c., it is customary to knit 20 the body portions of a two faced web—the opposite rows of loops of which mutually interlock within the web in a well known manner. In forming the waist portion it is usual to use 25 a tighter tension or to drop out a portion of the stitches comprising the balance of the web.

In knitting the garments (on a straight knitting machine having two parallel rows of 30 needles placed opposite each other after the manner of a Lamb machine) we begin preferably at the top or waist line by first setting up the work on the needles on both rows, to the width desired. This width may be sufficient 35 for one half of the garment provided it is desired to have no seam at the outside of the leg, or such width may extend from the middle waist line at the front or back to the outside leg seam at the hip, thus using two or 40 four pieces to complete the knitting of the main part of the garment, according as may be desired. Having placed the yarn upon the desired number of needles, the machine is arranged, as well known, to knit successively 45 upon the front and back rows of needles, thus producing a tubular web. Beginning at this end of the garment and placing the same yarn upon the opposite rows of needles at one and the same time, and then arranging the 50 cams of the knitting machine so as to knit alternately courses of loops upon the opposite

rows of needles, a tubular fabric is produced, the opposite sides of which are continuous and integral at the beginning end, like the bottom of a seamless bag, requiring nothing further to complete this portion of the garment. This tubular web is continued until the desired width of waist band is knitted, whereupon the cams are changed to cause the 55 opposite rows of needles to knit simultaneously and produce what is known as a two-faced fabric, the garment then being knitted as any garment of this class after thus changing the nature of the stitch. If desired, this process may be reversed, by beginning the 60 garment at the bottom with the two faced web and continuing until the waist line is reached, when the machine cams would be changed to produce the tubular waist portion. The garment would then be taken out 65 of the machine and the last course of loops of the knitting would be bound off in a manner well known,—either upon machines constructed for this purpose, called loopers, or by hand. This web being comparatively in- 70 elastic, produces the desired effect, giving a waist portion for the drawers, suit, vest, skirt, or other garment, which in connection with the non elastic band a hereinafter referred to 75 produces the required support at the waist portion and with much less expense than is occasioned by sewing on facings, and at the same time making a more desirable garment, because of the slightly elastic band. After 80 the waist portion of the garment is knitted of a double tubular web as described above, and a piece a , Fig. 2, of non-elastic fabric placed inside of it with its extremities sewed as at S to the knitted web, the elasticity of the waist portion of the garment will be limited to the 85 length of the inserted piece, thus giving all the advantage of a waist portion of a fixed size without the heretofore attendant expense of material and labor required to produce satisfactory results when the fixed band is 90 stitched in the usual manner upon the outside of the knitted fabric as such garments have heretofore been made.

In the drawings,—A indicates the body of the drawers, and B the tubular waist band. 95

While we have shown the invention as applied to drawers alone, we do not wish to be 100

understood as limiting ourselves to this special form of garment, as it is obvious that the invention can be applied to pants, skirts, shirts, and that class of suits known as combination garments.

We make no broad claim to a ribbed fabric finished off by a tubular web; in fact, make no claim to any fabric *per se*, but to a garment in which that portion fitting about the 10 waist of the wearer, is composed of a tubular web of less elasticity than the body portion with which it is integrally knitted together with the piece *a*.

Having thus described our invention, what 15 we claim is—

1. The herein described knit garment having the body portion formed of one-and-one-

rib fabric and a continuous waist portion of a double tubular web with a non-elastic fabric placed inside thereof and sewed to the knitted portion.

2. The herein described knit garment, the waist portion of which is formed of a double tubular web with a non-elastic fabric placed inside thereof and joined to the knitted fabric by stitches.

In witness whereof we hereunto set our hands in the presence of two witnesses.

STEPHEN B. LEWIS.
FRANKLIN F. LEWIS.
